UNITED STATES PATENT OFFICE.

FRANK A. BROWNE, OF WAYNE, PENNSYLVANIA, ASSIGNOR TO THE BARBER ASPHALT COMPANY, OF PHILADELPHIA, PENNSYLVANIA, A CORPORATION OF WEST VIRGINIA.

MIXING APPARATUS.

Application filed July 16, 1921. Serial No. 485,719.

To all whom it may concern:

Be it known that I, FRANK A. BROWNE, a citizen of the United States, residing in Wayne, in the county of Delaware and State of Pennsylvania, have invented certain new and useful Improvements in Mixing Apparatus, whereof the following is a specification, reference being had to the accompanying drawings.

10 My invention relates to mixing apparatus, and is concerned with apparatus especially suitable for mixing asphaltic or bituminous paving compositions, such as crushed stone and fluxed asphalt, for example. I 15 aim to make the apparatus simple, effective, durable, and convenient in service, and to enable it to be quickly and readily filled and emptied. How these and other advantages can be obtained through my invention 20 will appear from my description herein-after of the best embodiment of the invention at present known to me.

In the drawings, Fig. I is a plan view of a mixer constructed in accordance with 25 my invention.

Fig. II shows a longitudinal vertical section through the apparatus, taken as indicated by the line II—II in Fig. I.

Fig. III is a side elevation, certain parts 30 being broken away in places, or omitted entirely, to reveal parts behind them.

Fig. IV shows a transverse section through the apparatus, taken as indicated by the line IV—IV in Fig. I.

35 The mixer shown in the drawings comprises an open-topped tank 10 into which the material to be mixed can be readily shovelled or dumped. In the tank 10 are a couple of rotary agitators 11, 12, shown 40 as substantially horizontal and parallel. These agitators 11, 12 are just alike, and each of them comprises a multiplicity of inclined mixing blade members 13 radiating at various angles from a square shaft 45 15 whose rounded ends extend out through the tank ends 16 and are mounted in bearings 17 on brackets 18 which are attached to the ends of the tank and its base. The shafts 15 are removable through vertical 50 slots in the tank ends 16 which are normally closed by detachable cover plates 19 (Fig. IV). As shown, pairs of blade members 13 are set opposite one another and clamped

end to end about each shaft 15 with their inclined blades pitched at 45° angles to 55 the shaft axis and at a 90° angle to one another, and these blade pairs are arranged 120° apart in regular sequence, from end to end of the shaft. The agitators 11, 12 are connected together to revolve in opposite 60 directions by intermeshing gears 20, 21 of the same size, on the left-hand outboard ends of the shafts 15. The agitator blades 13 on the two ends of each shaft 15 are oppositely inclined in such a way that when 65 the shafts turn over toward one another the agitators tend to force the material being mixed from each end of the tank toward its center. Corresponding blades 13 on the two shafts 15 are 90° apart, so that they 70 do not interfere with one another when the mixer is running,—notwithstanding that the shafts are a shorter distance apart than twice the length of the blades. The agitators 11, 12 may be driven from a power 75 shaft 22, through a disconnectible clutch 23 and a pinion 24 which meshes with a gear 25 on one outboard end of the rear shaft 15. As shown, the clutch 23 is operated by a lever 26 fulcrumed to a bracket 27 which 80 is mounted on one of the longitudinal floor beams or girders 28 that support the tank 10 and the whole machine.

Referring, now, more especially to Figs. I and IV, it will be observed that the tank 85 bottom is rounded at 30, 30, coaxially (or substantially so) with each of the agitators 11, 12. As shown, the tips of the revolving blades 13 have just a fair, safe working clearance with these rounded bilges 30, 30, 90 so that no considerable amount of material can remain sticking to the tank walls undisturbed. The curved bilges 30, 30 are lined with sheets 31 of wear-resistant material, and on the outside of said bilges are 95 mounted arc-shaped heating chambers 33 (Fig. IV) consisting of approximately concaved superposed metal sheets (one "dished" as shown) secured together and riveted to the metal tank wall adjacent their edges. 100 On occasion, steam heated water, or hot oil may be admitted and circulated in these chambers 33 to keep the contents of the tank sufficiently soft or fluid during prolonged mixing.

105 In the bottom of the tank 10, between the

downward-sloping curved bilges 30, 30, is a dump opening, here shown as centrally located and as extending from end to end of the tank. During the mixing operation, 5 this dump opening is closed by means of movable covers 35 which are slidable lengthwise of the tank, in the direction of the agitator axes. As shown, the upper surfaces 36, 36 of the cover 35 are concaved upward 10 coaxially with the agitators 11, 12, and meet or intersect in a central elevated line or ridge extending lengthwise of the tank 10. The covers 35, 35, are slidable lengthwise outward beneath the upright tank end 15 16, so as to render the full length of the dump opening available for automatically emptying the tank 10 completely and expeditiously as the agitators 11, 12, revolve. The covers 35 are slidable as above de- 20 scribed directly in the dump opening itself, with their upper surfaces (formed by a protective sheet metal lining or wear plate 37 corresponding to the bilge linings 31 screwed fast to the covers proper) flush with the 25 inner surfaces of the tank bilges. Curved Z bars 38 are secured to the outer sides of the tank ends 16 with the edges of their depending flanges just clearing the surfaces of the covers 35. They are readily 30 adjusted to an accurate fit to take care of wear, etc., of the cover plate 37. The side edges or margins of the covers are rabbetted at 39, and underlie or "underlap" the corresponding edges of the dump opening in the 35 tank bottom somewhat. The covers 35 are supported on rails 40 extending lengthwise of the tank beneath the edges of the dump opening, by means of interposed antifriction wheels or rollers 41 pivoted between 40 metal strips 42 which are adapted to move in shallow grooves in the covers 35 and to overlap the edges of the rails 40. The rails 40 are secured by angle clips or brackets 43 to channel beams 44 extending length- 45 wise beneath the tank, and the upper corners or edges 45 of the margins of the covers 35 make a close sliding fit against these beams, so as to exclude dirt from the rollers 41 and the rails 40 as much as possible. 50 The beams or girders 44 are secured at either end to depending portions 46 of the tank ends 16 (which latter rest on the floor beams 28), by means of angle brackets or clips 47. For moving the covers 35 quickly and 55 easily, there are provided double acting fluid piston motors 50, whose cylinders are mounted on channel cross-bars 52 attached to the beams 28 by angle clips or brackets 53. The piston rods 54 of these motors 50 are 60 connected to lugs or ribs 55 depending from the covers 35, and braced therefrom by transverse and longitudinal webs 56, 57. Motive fluid (e. g., steam or compressed air) for operating the motors 50 is supplied through a 65 system of piping 58 and exhausted through a

system of piping 59, under control of oscillatory valves 60 and 61, whose crank arms are connected to a common actuating rod 62.

By shifting the rod 62 so as to turn the valves 60 and 61 through an angle of 90° 70 one way or the other, the two covers 35 can be simultaneously opened or closed very quickly and easily. When they are both open, the revolving blades will feed or sweep the entire contents of the tank 10 in- 75 to the dump opening in a very short time.

Water of condensation may be discharged from the cylinders of the motors 50 through relief cocks 63 whose crank arms are connected to a common actuating rod 64 oper- 80 able through a rocker 65 by a rod 66.

Having thus described my invention, I claim:

1. A mixer having substantially parallel rotary agitators, and comprising a tank with its bottom rounded to conform and in closely spaced relation to the peripheral path of movement of each of said agitators and having a dump opening between the downward-sloping bilges of said bottom, and a movable closure for said opening having upper surfaces concaved arcuately to form circular continuations of the tank bottom surfaces and meeting in an elevated longitudinal ridge which intersects the peripheral path of 95 rotation of both agitators.

2. A mixer having substantially parallel rotary agitators, and comprising a tank with its bottom rounded coaxially with each of said agitators and a dump opening extending from end to end of said tank between the downward-sloping bilges of said bottom, and a pair of closures for said opening slidable lengthwise therein and in opposite directions to uncover the opening and having 100 upper surfaces concaved coaxially with said agitators and meeting in an elevated longitudinal ridge, and a fluid pressure means for each closure to operate the same independently of the other closure.

3. A mixer having substantially parallel rotary agitators, and comprising a tank with its bottom rounded coaxially with each of said agitators and a dump opening extending from end to end of said tank between the downward-sloping bilges of said bottom, a pair of closures slidable endwise outward in opposite directions beneath the ends of the tank to allow it to be completely emptied through said opening.

4. A mixer having substantially parallel rotary agitators, and comprising a tank with its bottom rounded coaxially with each of said agitators and a dump opening between the downward-sloping bilges of said bottom, support rails extending lengthwise of said tank beneath the opposite edges of said opening, a closure means for said opening slid- 115 able lengthwise of said tank, and wheels sup- 120 porting the closure and running on said rails.

5. A mixer having substantially parallel rotary agitators, and comprising a tank with its bottom rounded coaxially with each of said agitators and a dump opening between 5 the downward-sloping bilges of said bottom, a movable closure for said opening slidable lengthwise therein and having upper surfaces, flush with the inner surfaces of the tank bilges, concaved coaxially with said 10 agitators and meeting in an elevated longitudinal ridge, the side edges of said closure underlapping the corresponding edges of said dump opening, supporting rails, and wheels supporting said underlapping side 15 edges of the closure and running on the rails.

6. A mixer comprising a pair of rotary agitators, a tank having its bottom rounded to conform to the peripheral path of rotation of the agitators and having a dumping 20 opening in its bottom wall, a pair of closures for said opening, each having concaved sides constituting arcuate continuations of the tank bottom, said closures abutting at the 25 transverse medial line of the casing and opening in opposite directions, a cylinder and piston beneath each closure, and a connection between each closure and its correlated piston.

7. A mixer comprising a pair of rotary 30 agitators, a tank having its bottom and lower end walls rounded to conform to the peripheral path of rotation of the agitators, said tank having an opening in its bottom wall, a closure for said opening slidable endwise 35 of the tank and having concaved sides forming arcuate continuations of the tank bottom surfaces, and joint forming plates adjustably fitted to the end walls of the tank for move-

ment toward and away from the closure to effect a tight compensating joint between the 40 closure and tank end walls.

8. A mixer comprising a tank, the opposed walls of which are formed with opposed pairs of slots entering the edges of said walls, agitator shafts fitted in said tank by passing 45 the ends of the shafts through the slots, plates filling said slots and seated between the edges thereof subsequent to the insertion of the shafts, lateral extensions of the plates bolted to said walls and bearings for supporting 50 said shafts.

9. In a mixer, a pair of spaced beams, a mixing tank supported upon and between said beams and having a lower dumping opening, a pair of rails, each supported upon 55 one of said beams, a sliding closure for the tank opening, and wheels supporting the closure and running on said rails.

10. A mixer comprising agitators and a tank having a rounded bottom and a dumping opening formed therein, a ridged slideable closure for the opening, a reinforcing casting conforming to the outer surface of the closure and secured thereto, rails, wheels carried by said casting and running on said 65 rails, a web formed with the casting, a cylinder, and a piston and piston rod cooperating therewith, the latter having a connection to the web.

In testimony whereof, I have hereunto 70 signed my name at Philadelphia, Pennsylvania, this 8th day of July 1921.
